SYNCHRONOUS-MOTOR ELECTRIC AUDIBLE-SIGNAL CLOCK

Application filed June 13, 1930. Serial No. 460,860.

This invention relates to an improvement in electric audible-signal clocks such as alarm clocks, strike clocks, chime clocks, or combinations of the same and relates in particular to electric clocks of the character referred to which are driven by continuously-rotating synchronous motors and of the same general type as that shown in my co-pending application filed June 13, 1930, Serial No. 460,861, and also in my co-pending application filed March 8, 1930, Serial No. 434,347.

The main object of this invention is to provide an electric clock of the type referred to with improved and substantially trouble-free means for periodically coupling an audible-signal mechanism to the continuously-rotating synchronous motor utilized for driving the time-indicating means.

With the above and other objects in view, as will appear from the following, my invention consists in an electric audible-signal clock characterized by its provision with a continuously-rotating synchronous electric motor; time-indicating means driven thereby; a normally-idle audible-signal mechanism actuatable by the said motor; means for coupling the said audible-signal mechanism to and uncoupling the same from the said motor, including a pair of complementary gears, one of which is constantly driven by the said motor and the other of which is operatively connected to the said audible-signal mechanism, and an intermediate gear mounted with capacity for being shifted edgewise into and out of position to interconnect the said pair of complementary gears; and an automatic control-mechanism itself controlled by the said synchronous motor and operatively connected to the said intermediate gear for moving the same edgewise into and out of its gear-interconnecting position for automatically effecting the periodic operation of the said audible-signal mechanism.

My invention further consists in an electric audible-signal clock characterized as above and having certain other details of construction and combinations of parts as will be hereinafter described and particularly recited in the claims.

In the accompanying drawings:

Fig. 1 is a view in front elevation of a synchronous-motor alarm-clock movement illustrating one form which my invention may assume, the parts being shown in the positions due to them when the alarm-mechanism is idle;

Fig. 2 is a view thereof in side elevation;

Fig. 3 is a view in front elevation corresponding to Fig. 1, but showing the parts in the positions due to them when the alarm-mechanism has been automatically coupled to the motor for actuation thereby;

Fig. 4 is a detached perspective view of the gear-shifting lever, together with the gears organized therewith; and

Fig. 5 is a detached perspective view of the resilient alarm-control lever.

In the alarm clock herein chosen for the illustration of my invention, I employ a synchronous motor which may be of any approved form and in principle is so well understood in the art as to require no description other than to say that it is enclosed within a casing 10 secured to the rear movement-plate 11 of the movement, and is provided with an arbor 12 forwardly projecting through an aperture 13 in the said rear movement-plate, and carrying a driving-pinion 14 meshing into and driving a gear-wheel 15 mounted upon an arbor 16 journalled at its rear end in the rear movement-plate 11, already referred to, and at its front end journalled in the complementary front movement-plate 17 coupled to the said rear movement-plate by the usual pillars 18.

The arbor 16, above referred to, carries near its rear end a pinion 19, meshing into and driving a minute-wheel 20 staked upon the center-arbor 21. The said center-arbor 21 is journalled in the rear and front movement-plates 11 and 17 and projects forwardly from the latter and carries at its extreme forward end a minute-hand 22 indicated by broken lines in Fig. 2.

Immediately forward of the front movement-plate 17 the center-arbor 21, above described, has secured to it a cannon-pinion 23 meshing into and driving a dial-wheel 24, carrying a dial-pinion 25 and mounted to-

gether with the same upon a stud 26 forwardly projecting from the front movement-plate 17 in the usual manner of clock-dial work. The dial-pinion 25 meshes into and drives an hour-wheel 27 staked upon an hour-sleeve 28, sleeved over and rotating freely upon the projecting forward end of the center-arbor 21, and carrying at its forward end the usual hour-hand 29, indicated by broken lines in Fig. 2.

The parts previously described constitute a synchronous time-train for indicating the time in consonance with the beat of an alternating current, in the usual manner of synchronous-motor electric clocks.

The dial-pinion 25 before referred to also meshes into and drives an alarm-cam wheel 30 staked to the hub 31 of a sleeve-like alarm-cam 32 mounted upon the forward end of an alarm-set staff 33 with freedom for relative rotation and axial movement thereon. The said sleeve-like alarm-cam 32 is formed with the usual alarm-cam contour, consisting of a rise 34, a low-point 35, and a high-dwell 36.

The alarm-set staff 33 carries at its forward end a radially-offsetting alarm-cam finger 37 co-acting with the outer face of the alarm-cam 32 in the usual manner of alarm clocks, and at its rear end mounts the usual knurled finger-button 38.

The rear end of the hub 31 of the alarm-cam 32 bears against the front face of an alarm-control lever 39 preferably made of spring-metal and secured at one end by means of a rivet 40 to the front movement-plate 17, and provided intermediate its ends with a slot 41 for the clearance of the alarm-set staff 33, and at its opposite end carrying a cam-finger 42 projecting rearward through a clearance-opening 43 in the said front movement-plate for engagement with the edge of a vertically-arranged gear-shifting lever 44.

The gear-shifting lever 44 just above referred to is formed of sheet-metal and has its lower end bent rearward and upward to form an arm 45 rearwardly-spaced from the body proper of the lever 44, as shown in Figs. 2 and 4, to form a space 46 for the accommodation of what I shall, for convenience of description, refer to as a driven gear or pinion 47 and for the accommodation of an intermediate gear or pinion 48, which latter is constantly in mesh with the driven gear or pinion 47 and is shiftable edgewise, as will hereinafter appear, for being meshed into the constantly-rotating pinion 14 upon the shaft 12 of the synchronous motor 10.

The said lever 44 is pivotally mounted upon the reduced forward end of an arbor 49 upon which the driven gear or pinion 47 before referred to is staked and which bears at its opposite ends in the front and rear movement-plates 17 and 11. A shoulder 50 upon the said arbor 49 serves to prevent the rearward

displacement of the lever, while a collar 51 bearing against the front face of the said gear-shifting lever 44 proper, serves to prevent its forward displacement while permitting free swinging movement with respect to the said arbor 49. The intermediate gear or pinion 48 is mounted upon an arbor 52 journaled at its forward end in the lever 44 proper and at its rear end in the upturned arm 45 thereof.

Near its rear end, the arbor 49, upon which the lever 44 rocks, as before set forth, has staked to it a hammer-actuating wheel 53 having its periphery formed with triangular teeth 54 coacting with an actuating-pin 55 forwardly-offsetting from a hammer-arm 56 about midway the length thereof. The said hammer-arm is formed of sheet-metal and is provided at its upper end with an integral cross-bar 57 terminating at its respective opposite ends in trunnions 58 rocking in suitable bearing-openings in the front and rear movement-plates 17 and 11.

The hammer-arm 56 is swung from right to left so as to cause its head 59 to strike a bell 60 by means of a torsion-spring 61, the said bell being supported by a U-shaped bracket 62 depending from the lower edge of the front movement-plate 17.

To provide for manually shutting off the alarm-mechanism after the same has been automatically sounded, I employ a horizontally arranged reciprocating alarm shut-off plunger 63 mounted for reciprocation in the front and rear movement-plates 17 and 11, as shown in Fig. 2, and carrying a conical shut-off cam 64 adapted to engage the left-hand edge of the gear-shifting lever 44 when the said plunger is moved, as indicated by broken lines in Fig. 2, to swing the said lever from left to right against the counter-urge of a helical spring 65, as required to de-mesh the intermediate pinion 48 from the driving-pinion 14, as shown in Fig. 1 of the drawings.

In the operation of the alarm clock herein chosen for the illustration of my invention, the synchronous motor effects the continuous rotation of the minute-hand 22, hour-hand 29, the alarm-cam 32, the motor-pinion 14, but since the gear-shifting lever 44 is normally held in its retired position, as shown in Fig. 1, together with the intermediate pinion 48, by the alarm-control lever 39, the hammer-actuating wheel 53 will remain stationary and the hammer-arm 56 will not be vibrated for striking the bell 60.

Now, in the continued rotation of the alarm-cam 32, the low-point 35 thereof will be brought into registration with the alarm-cam finger 37, so that the cam-wheel 30, together with the cam 32 and the hub 31, will be permitted to snap forward under the urge of the resilient alarm-control lever 39, provided, of course, the manual shut-off plunger 63 has been previously moved into its retired

position, as shown by full lines in Fig. 2, by means of its finger-button 66 to permit such action.

When the cam 32 and its hub 31 are snapped forward by the resilient alarm-control lever 39, as just above described, the cam-finger 42 of the latter will move forward and permit the gear-shifting lever 44 to be swung from right to left by the spring 65, with the effect of meshing the intermediate pinion 48 with the continuously-rotating pinion 14, thereby coupling the hammer-actuating wheel 53 to the said pinion 14 and hence to the motor for being rotated thereby.

15 The rotation of the hammer-actuating wheel 53 as thus effected will cause the teeth 54 thereof to alternately swing the hammer-arm 56 outward and then permit the same to be snapped inward by the spring 61 at close 20 intervals so as to effect the sounding of an alarm or other audible signal.

When it is desired to check the sounding of the alarm, the user of the clock slides the alarm shut-off plunger 63 forward by means 25 of its finger-button 66 and thereby causing the conical cam 64 to swing the gear-shifting lever 44 from the position in which it is shown in Fig. 3 to the position in which it is shown in Fig. 1, with the effect of de-meshing the intermediate pinion 48 from the continuously-rotating pinion 14 and hence disconnecting the hammer-actuating wheel 53 from the synchronous motor.

35 The continued rotation of the alarm-cam wheel 30 will eventually cause the alarm-cam 32, together with the said wheel, to move axially inward under the alarm-cam finger 37 and thus cause the hub 31 to flex the resilient alarm-control lever 39 inward, with the effect 40 of engaging the cam-finger 42 thereof with the adjacent edge of the gear-shifting lever 44 to move the same from the position in which it is shown in Fig. 3 into the position in which it is shown in Fig. 2.

45 The alarm-control lever 39 will now have assumed the task of holding the said gear-shifting lever 44 in its retired position, until the next automatic release of the alarm after the manual shut-off device has been retired 50 out of action by sliding the plunger 63 rearward, as already described.

By employing an intermediate pinion which is shiftable edgewise, the coupling and uncoupling of the alarm-actuating mechanism or other suitable audible-signal mechanism is readily accomplished without occasioning a jamming of the parts, which might result in the stalling of the entire clock.

60 It will be understood by those skilled in the art that my invention may assume varied physical forms without departing from my inventive concept, and I, therefore, do not limit myself to the specific embodiment herein chosen for illustration, but only as indicated in the appended claims.

I claim:

1. In an electric audible-signal clock, the combination with a continuously-rotating electric motor; time-indicating means driven thereby; a normally-idle audible-signal mechanism actuatable by the said motor; means for coupling the said audible-signal mechanism to and uncoupling the same from the said motor, including a pair of complementary gears, one of which is constantly driven by the said motor and the other of which is operatively connected to the said audible-signal mechanism, and an intermediate gear mounted with capacity for edgewise movement into and out of position to interconnect the said pair of complementary gears; and an automatic control-mechanism including a spring operatively connected to the said intermediate gear and exerting an effort to move the same edgewise into position to interconnect the said pair of complementary gears, and a cam for moving the said intermediate gear into its retired position against the counter-urge of the said spring. 70

2. In an electric audible-signal clock, the combination with a continuously-rotating electric motor; time-indicating means driven thereby; a normally-idle audible-signal mechanism actuatable by the said motor; means for coupling the said audible-signal mechanism to and uncoupling the same from the said motor, including a driving gear propelled by the said motor, a driven gear operatively connected to the said audible-signal mechanism, and an intermediate gear mounted with capacity for edgewise movement and constantly in mesh with the said driven gear; and an automatic control-mechanism including a spring operatively connected to the said intermediate gear and exerting a constant effort to move the same edgewise into mesh with the said driving gear, and a cam for moving the said intermediate gear out of mesh with the said driving gear against the counter-urge of the said spring. 90

3. In an electric audible-signal clock, the combination with a continuously-rotating electric motor; time-indicating means driven thereby; a normally-idle audible-signal mechanism actuatable by the said motor; means for coupling the said audible-signal mechanism to and uncoupling the same from the said motor, including a pair of complementary gears, one of which is constantly driven by the said motor and the other of which is operatively connected to the said audible-signal mechanism, a gear-shifting lever mounted with capacity for pivotal movement concentrically with respect to one of the said pair of complementary gears, and an intermediate gear mounted upon the said gear-shifting lever for edgewise movement therewith and constantly in mesh with the gear with respect to which the said lever is concentrically mounted; and an automatic control- 110

115

120

125

130

mechanism including a spring connected to the said gear-shifting lever and exerting an effort to swing the same in a direction required for meshing the said intermediate gear with the other of the said pair of complementary gears, and a cam for swinging the said gear-shifting lever into its retired position against the counter-urge of the said spring.

4. In an electric audible-signal clock, the combination with a continuously-rotating electric motor; time-indicating means driven thereby; a normally-idle audible-signal mechanism actuatable by the said motor; means for coupling the said audible-signal mechanism to and uncoupling the same from the said motor, including a driving gear propelled by the said motor, a driven gear operatively connected to the said audible-signal mechanism, a gear-shifting lever mounted with capacity for pivotal movement concentrically with respect to the said driven gear, and an intermediate gear mounted upon the said gear-shifting lever for edgewise movement therewith and constantly in mesh with the said driven gear; and an automatic control-mechanism including a spring connected to the said gear-shifting lever and exerting an effort to swing the same in a direction required for meshing the said intermediate gear with the said driving gear, and a cam for swinging the said gear-shifting lever into its retired position against the counter-urge of the said spring.

In testimony whereof, I have signed this specification.

ELOF L. CARLSON.
